UNITED STATES PATENT OFFICE.

WILLIAM A. STUART, OF TACOMA, WASHINGTON.

WATER-ELEVATING DEVICE.

1,416,075.

Specification of Letters Patent. Patented May 16, 1922.

Application filed October 9, 1920. Serial No. 415,729.

To all whom it may concern:

Be it known that I, WILLIAM A. STUART, a citizen of the United States, residing at Tacoma, in the county of Pierce and State 5 of Washington, have invented new and useful Improvements in Water-Elevating Devices, of which the following is a specification.

This invention relates to water power 10 machines and has for its object the provision of a device designed for lifting or forcing water from streams and the like to points above gravity flow, such as highlands, reservoirs, pressure tanks, storage tanks or basins, 15 and the like.

An important and more specific object is the provision of a device for this purpose which is operated by water flow only, the device operating on the principle of the 20 hydraulic ram and being entirely automatic in operation as long as water under slight head or pressure is fed to the device, the device operating to expel forcibly a portion of the water, the remainder of the water 25 being of course wasted after its power is spent.

A further object is the provision of a device of this character which is of sufficient power to be of actual service in lifting 30 water in sufficient quantities to render its efficiency of value, it being of course apparent that the cost of operation is practically nil inasmuch as it is the water head alone which is employed as a motive force.

An additional object is the provision of a 35 device of this character which will be comparatively simple and inexpensive in manufacture and installation, highly efficient and powerful in use, durable in service, and a 40 general improvement in the art.

With the above and other objects and advantages in view, the invention consists in the details of construction to be hereinafter more fully described and claimed and illustrated in the accompanying drawings in which—

Figure 1 is a side elevation of the complete device,

Figure 2 is a plan view,

50 Figure 3 is an end elevation,

Figure 4 is a vertical sectional view through one end of the machine on a larger scale,

Figure 5 is a similar view taken at right 55 angles to Figure 4,

Figure 6 is an enlarged vertical sectional

view through the lower portion of one end of the device and showing the valve mechanism in use, and

The remaining figures are detail views. 60

Referring more particularly to the drawings, the numeral 10 designates a supporting frame which is formed of any suitable material such as angle iron, bars, or the like, and which may be of any desired 65 height and of course of rigid construction. Mounted upon the top of this frame is a reservoir tank 11 which extends laterally beyond the sides of the frame, as clearly indicated, and connected with this reservoir 70 tank is a flume 12 from which water is conducted to the tank from any desired source which might be a stream or any other desired body of water. It is of course necessary that a constant current be supplied to 75 the reservoir in order to effect operation of the parts to be described.

The numeral 12 designates the base of the device upon which the frame 10 is mounted and rising from this base at opposite 80 sides of and spaced from the frame and projecting ends of the tank 11, are upright cylinders 13 within each of which is operable a piston 14 carried by a rod 15 provided at its upper end with a cross head 16 vertically 85 movable between guides 17. At the bottom of each cylinder 13 is a passage member 18 which communicates with the lower end of the cylinder and which communicates with a pipe 19. The pipes leading from the two 90 cylinders are connected to a T 20 from which extends a discharge pipe 21. Located in the passage member adjacent its juncture with the pipe 19 is a valve seat 22 normally closed by a gravity valve 23 carried by a 95 stem 24 slideable through guides 25. A suitable clean-out plug 26 is provided in the passage member below the valve seat 22 whereby access may be had for effecting adjustments or for cleaning out accumulations. 100 Connected with the passage member 18 between the cylinder 23 and valve seat 22 is an upwardly inclined pipe 27 which leads into the bottom of the reservoir tank 11.

Located at the lower end of the pipe 27 105 is a spider bearing 28 through which is slideable a stem 29 of a valve 30 and connected with this stem is a flexible member 31 such as a cable or chain which extends upwardly beyond the top of the pipe 27 and 110 which is connected with an adjustable eye bolt 32 carried by one end of a bar 33 which

is pivoted intermediate its ends upon a bracket 34 mounted upon the bottom of the tank 11. The other end of this bar 33 is notched, as indicated at 35, and mounted upon this end is a weight 36 having a tongue 37 engagable within any one of the notches 35. The purpose of this weight and bar is to counter-balance the valve 30 and its associated parts so that the valve 30 will be normally held closed against a seat 38 at the bottom of the pipe 27 where the latter communicates with the passage member 18.

Journaled upon cross bars 39 of the frame 10 are walking beams 40 which carry at 15 their ends tanks 41 and these tanks are connected in pairs by yokes 42 disposed outwardly of the cylinders 13. It is of course apparent that the connection of the walking beams with the tanks 41 must be pivotal so 20 that the tanks 41 will remain always in horizontal position irrespective of the positions of the walking beams. These tanks extend partly below the projecting ends of the reservoir tank 11 in position to receive 25 water discharged from the latter. At each end the bottom of the tank 11 is provided with a pair of openings 43 immediately above the tanks 41 and each of these holes is normally closed by a flap valve 44 carried 30 by a pivoted arm 45. Slidable through guides 46 on each end of the tank 11 are vertical rods 47 which extend downwardly below the tank a considerable distance and which are connected at their upper ends with 35 the flap valves 44 by flexible members 48.

Formed in one end of each of the tanks 41 is an opening 49 normally closed by a valve 50 carried by links 51 and to which is connected a flexible member 52, such as a 40 chain or the like, which is also connected with a bracket 53 depending from the tank 11.

The operation of the device is as follows:

Initially, the device must be so arranged 45 that the tanks 41 at one end of the device are in their highest positions engaging against the bottom of the tank 11. At this time and in fact at all times, the pipes 27 are full of water and the valves 30 are normally closed, being held in closed position by the weighted lever bars 33. When the tanks 41 at one side are in their uppermost 50 positions, the bottoms of the tanks will engage against the lower ends of the rods 47 and move them upwardly which will result 55 in upward movement of the flap valves 44. The holes 43 in the bottom of the tank 11 will then be uncovered and the water within the tank will flow into these elevated tanks 60 41. When the tanks 41 fill they will gravitationally descend, carrying with them the piston rod 15 and the piston 14. At the same time the tanks 41 at the other end of the device will be elevated and will engage 65 the rods 47 and open the other flap valves

44 which will result in filling of the other tanks 41. At the time that the second mentioned tanks 41 are filling the first mentioned tanks 41 will have reached their lower positions whereupon the flexible member 52 connected with the bracket 53 will cause the valves 50 to swing upwardly, uncovering the openings 49 whereupon the water within the first mentioned tanks 41 will flow out through the openings 49. As the tanks 41 are connected by the connecting rods or links 41^a with the cross heads 16 it will be seen that as either pair of tanks 41 moves upwardly the pistons 14 in the associated cylinders 13 will likewise be moved upwardly, whereupon the valves 23 will be closed and the valves 30 opened whereupon the water within the pipes 27 will flow into the passage members 18 and into the cylinders 13. When the pistons 14 reach the upper limit of their movement the weighted lever 33 will operate to reclose the valves 30. As the tanks 41 are filled and descend, the associated pistons 14 will move downwardly whereupon the water within the cylinders 13 will be forced therefrom, through the passage members 18 and will unseat the valves 23 and pass out through the pipes 19 and out through the pipe 21 which leads to wherever the water is desired. This action is continuous as long as water is supplied to the tank 11 and it is of course apparent that the tanks 41 at both sides of the machines will be alternately filled and emptied and the piston correspondingly actuated. In this way it will be seen that water will be constantly forced by the device to any desired location, the spent water being of course lost.

From the foregoing description and a study of the drawings it will be apparent that I have thus provided a simply constructed device which comprises few moving parts, which will be positive in action, efficient in service, and which will perform all the functions for which it is intended.

While I have shown and described the preferred embodiment of my invention, it is of course to be understood that I reserve the right to make such changes in the form, construction, and arrangement of parts as will not depart from the spirit of the invention or the scope of the subjoined claims.

Having thus described my invention, I claim:

1. A device of the character described comprising an elevated tank provided with a water inlet and provided in its bottom with normally closed openings, a walking beam pivoted beneath said tank, upright cylinders at the ends of the tank, pistons within said cylinders, tanks carried by the ends of the walking beam and connected with said pistons, pipes leading into the bottom of said first named tank and con-

ected with the lower ends of said cylinders, normally closed valves cutting off communication between said pipes and said cylinders, check valved outlet pipes connected 5 with said cylinders, and means operated by up and down movement of said movable tanks for uncovering said openings and opening said first named valve.

2. A device of the character described 10 comprising an elevated tank provided with a water inlet and provided in its bottom with normally closed openings, a walking beam pivoted beneath said tank, upright cylinders at the ends of the tank, pistons within 15 said cylinders, tanks carried by the ends of the walking beam and connected with said pistons, pipes leading into the bottom of said first named tank and connected with the lower ends of said cylinders, normally 20 closed valves cutting off communication between said pipes and said cylinders, check valved outlet pipes connected with said cylinders, and means operated by up and down movement of said movable tanks for uncovering 25 said openings and opening said first named valve, said movable tanks being provided with openings, valves movable to cover and uncover said last named openings, and flexible members connected with said last

named valves and secured with respect to 30 the first named tank for automatically opening said last named valves when said movable tanks reach their lower positions.

3. A device of the character described 35 comprising a supporting frame work, a tank carried by said frame and provided with a water inlet and provided in its bottom with an opening, a pivoted arm within said tank carrying a valve for closing said opening, a walking beam, a movable tank carried by 40 the walking beam and disposed below said outlet opening in the first named tank, an L-shaped rod slidale along one end of said first named tank, a link connection between said rod and said valve, a bracket member 45 on said rod, said movable tank being provided in one end with an outlet opening, an upwardly swinging valve member mounted within the movable tank and normally closing the outlet opening therein, and a flexible 50 member connected with said last named valve and with said rod whereby to close the first named valve and open the last named valve when the movable tank is in its lowermost position.

55 In testimony whereof I affix my signature.

WILLIAM A. STUART.
